LAUNDRY SHAKE-OUT DEVICE

Fred A. Mann, Jr., South Bend, and John F. Halladay, Elkhart, Ind.

Application July 11, 1949, Serial No. 103,986

17 Claims. (Cl. 38—143)

1

This invention relates to a device for smoothing laundered items, and particularly to a device adapted for use in commercial laundries which have roller type ironing machines for ironing flat work.

The laundering of flat work in a commercial laundry, such as the laundering of sheets, pillow-cases, large towels, bedspreads, tablecloths and other items, entails the wrinkling and compacting of the damp work pieces into a compact mass of small compass. Consequently, when work pieces are to be fed into an ironing machine, it is necessary that they be extended to their flat form to avoid ironing in a manner which would cause creases or wrinkles in the finished work. Where the work pieces employed are small, an operator can grasp the piece at an edge thereof and give it a shake to extend it to a condition where it is adapted to be received in an ironing machine. Where large flat pieces, such as sheets, large towels, tablecloths, large scarves, bedspreads and the like, are laundered, however, manual spreading or extending of the damp work piece is difficult and time consuming. Such items are of a size that, in order to insure proper positioning of the leading edge of the item into the ironing machine, it is necessary that two operators do the work, grasping opposite sides of the work piece and introducing it into the ironer and stretching or smoothing it as it is fed into the ironer. Where such large work pieces come to the iron feeders in a wadded condition in which they are commonly discharged from the washing machine, a large amount of time and effort is required by the ironer operators to stretch and smooth the sheet and position it to be fed to the ironer in proper squared relation relative to the direction of travel of the work piece through the ironer. The ironing machine therefore cannot operate at its rated capacity, and considerable loss is experienced by the laundry.

It is the primary object of this invention to provide a device which is easily and rapidly operated by a single attendant and which will permit the discharge of work pieces to a delivery point adjacent the feeding end of an ironing machine in an extended condition ready for insertion into the ironer.

A further object is to provide a device of this character which is novel and simple in construction, which will remove wrinkles from flat laundered articles, and which will remove excess moisture therefrom so as to reduce the time required for ironing, thereby permitting the speed of the ironer to be accelerated.

2

A further object is to provide a device of this character having a conveyor adapted to engage a laundered article at a central part thereof and to carry the item to a discharge point with its side portions suspended alongside a guide carrying a plurality of nozzles from which air is emitted in jets to vibrate said side portions.

A further object is to provide a device of this character having a conveyor for gripping the central portion of a laundered item and conveying it, with its side portions suspended and positioned within the influence of vibrating means, to a delivery station at which is located spreader means for laterally outwardly deflecting said suspended side portions and thereby facilitating grasping thereof by operators located at said station on opposite sides of said spreader.

A further object is to provide a device of this character having a conveyor positioned above oppositely inclined panels which are adapted to be engaged by side portions of a laundered item propelled by the conveyor, and also having guides projecting forwardly from the panels at the feed end of the device to spread the laundered item as it is gripped by said conveyor and advanced toward said panels.

Other objects will be apparent from the following specification.

In the drawings:

30 Fig. 1 is a perspective view of the device.
Fig. 2 is a view of the device in side elevation with parts broken away to illustrate the interior construction thereof.

35 Fig. 3 is a fragmentary detail sectional view taken on line 3—3 of Fig. 1.

35 Fig. 4 is an end view of a modified embodiment of the invention.

Fig. 5 is a fragmentary side view of a modified embodiment of the invention.

40 Fig. 6 is a fragmentary sectional view taken on line 6—6 of Fig. 5.

Fig. 7 is an enlarged fragmentary sectional view similar to Fig. 6 but illustrating another modified embodiment.

45 Referring to the drawings, and particularly to Figs. 1 to 3 thereof, the numeral 10 designates a pair of spaced longitudinal frame members, such as pipes, from the opposite ends of each of which extend upright portions 11 extending substantially vertically at their lower portions and inclined upwardly at 12. The inclined portions 12 terminate in spaced relation and have plate portions 13 secured at their ends and in turn secured to elongated rigid frame members 14 which are connected by suitable spacers (not shown). The

frame uprights 12 are connected to the longitudinal frame members 14 in spaced relation to the opposite ends of said frame members 14 so that the latter project beyond the frame defined by the parts 10—12. Longitudinally extending inclined panels 15 are secured at their opposite ends to the inclined frame portions 12, said panels being formed of any suitable material, such as metal, plywood or the like. The frame supports the longitudinal portions 14 at a substantial elevation, and preferably an elevation greater than one-half the dimension of the largest laundered item to be used therewith. The panels 15 which diverge downwardly and outwardly from the frame portions 14 extend for the major portion of the height of the frame and, as here shown, for the full length of the inclined portions 12 of said frame.

The longitudinal frame members 14 mount suitable bearings or journals (not shown) at each end thereof, upon which are rotatably mounted a front roller 16 and a rear roller 17, said rollers being positioned with their axes substantially horizontal and transverse of the frame members 14, and their peripheries projecting beyond the ends of the frame members 14. A belt is trained around the rollers 16 and 17, said belt including an upper horizontal run 18 preferably of a width substantially equal to the spacing between the frame members 14. A run 19 of the belt is inclined downwardly and rearwardly from the front roller 16 and extends around a roller or pulley 20 which is suitably journaled upon a cross-shaft 21 which may be mounted in bearings 22, best seen in Fig. 4, in turn carried by upright cross-braces 23 which reinforce each of the panels 15. An elongated bar or yoke 24 is preferably pivoted upon the shaft 21, and at its lower end carries a shaft 25 upon which is journaled a roller or pulley 26. The belt is trained in a run 27 downwardly around the upper pulley 20 and thence forwardly and downwardly around the lower pulley 26. From the pulley 26 a run 28 of the belt extends rearwardly and upwardly to the rear roller 17. The upper free end of the bar or yoke 24 is preferably urged by a spring 29 anchored at one end thereto and at its opposite end to an anchor member 30 preferably carried by one of the panel reinforcing members 23. The spring 29 serves normally to so position the shiftable pulley or roller 26 as to cause the belt to be drawn taut. The shaft 25 preferably mounts a second pulley 31 around which is trained a belt 32, in turn trained around a pulley 33 carried by the shaft 34 of an electric driving motor 35. The drive motor 35 is preferably mounted upon a support or framework 36 carried by the lower part of the frame of the device, as by the frame parts 10.

A second outer frame is provided in the device which preferably includes transverse bottom frame parts 40, such as angle irons, upon which the ends of the frame parts 10—11 bear, and to which they may be soldered, bolted, welded or otherwise fixedly secured. The frame parts 40 project laterally outwardly into spaced relation to the frame parts 10 and 11, and upright frame parts 41 are carried by the outer ends of each of the lower horizontal frame parts 40. The frame parts 41 merge with inclined upper frame parts 42 spaced outwardly a substantial distance from the adjacent panels 15, and the upper ends of the inclined frame parts 42 at each end of the device are connected by upper cross-frame members 43. The cross-frame members 43 are positioned in spaced relation above the frame mem-

bers 14. The end frame parts may be suitably reinforced and interconnected by the longitudinal brace members 44. The upper cross-braces 43 at the opposite ends of the outer frame are preferably provided with two or more spaced apertures through which extend elongated substantially upright screw-threaded shafts 45. Nuts or other internally screw-threaded fittings 46 which are threaded upon said shaft serve as stops 10 engaging the upper surface of the frame members 43 and positioning the members 45. Each of the members 45 preferably has an enlarged head 47 at its lower end, said members passing through apertures in horizontal flanges of angle brackets 48 which bear on said heads 47. The angle brackets 48 are secured to opposite side members 49 of an elongated rigid frame unit of substantially the same length as the frame members 14 and suspend said frame unit in a position above the frame members 14 and substantially parallel thereto. The members 46 provide means for positioning the frame members 49 and for leveling the same. It will be understood that the frame members 49 are interconnected by suitable cross-braces (not shown) and constitute a substantially rigid elongated frame unit of substantially the same width as the frame unit of which the members 14 form a part.

The frame unit 49 carries suitable journals (not shown) upon which a front roller or pulley 50 and a rear roller or pulley 51 are journaled. One of these rollers is adjustably mounted, for which purpose lugs 52 are provided carried by the frame members 49 and threadedly mounting or supporting an elongated screw-threaded member 53 adjustably positioned with respect to the frame members 49 and abutting or connected at one end to a projecting portion 54 of a shaft mounting a roller, here illustrated as the roller 50. The rollers 50 and 51 are of a diameter greater than the vertical dimensions of the frame unit 49 and are preferably substantially of the same axial dimensions as the rollers 16 and 17.

A belt or other web is trained around the rollers 50 and 51, the same having an upper run 55 and a lower run 56. In the normal position of the parts, the run 56 of this belt will preferably contact the run 18 of the belt trained around the rollers 16 and 17 so that said belt runs will be in drive-transmitting relation, the belt 55, 56 being an idler and traveling only as a result of its contact with the run 18 of the driven belt. It will be observed from Figs. 1 and 2 that the roller 50 at the feeding end of the machine is positioned with its axis located in slightly rearwardly spaced relation to the axis of the roller 16.

A pair of guides or spreaders are carried by the device at each end thereof. These spreaders include an upper front spreader formed of rigid wire or any other suitable material having longitudinal runs or portions 57 anchored to the frame members 14 at the rear ends 58 thereof. The runs 57 of this spreader extend alongside and are laterally spaced from the frame members 14, and at their forward ends 59 are bent around the front roller 16 at a level slightly below the level of the belt run 18 and forwardly spaced from the roller 16. A lower front spreader is preferably formed of tubular material, such as copper tubing of comparatively small bore, the same being anchored or secured, as by means of clips or brackets 60, to the frame portions 12 adjacent the junction of said frame portions 12 with the frame portions 11. The lower tubular spreader is generally of U-shape with its end por-

tions 61 inclined forwardly and upwardly from the brackets 60 and thence converging upwardly and inwardly at portions 62 which merge in a central curved portion 63. The central curved portion 63 is preferably positioned substantially directly below the curved portion 59 of the upper spreader, but the arms 61 of this spreader are spaced apart laterally a greater distance than the arms 57 of the upper spreader. The spreader tube 61-63 has a plurality of apertures or jets 64 formed therein facing outwardly and laterally with respect to the longitudinal dimension of the device. At the rear of the device a rigid wire spreader has a longitudinal portion 65 extending alongside the frame portions 14, the same preferably being secured to the panel 15 or the frame of said panel at the inner face or portion thereof, for which purpose the forward end of the spreader is bent at 66. The spreader 65, 66 may be U-shaped with its central portion extending around and clear of the roller 17 or may comprise two elongated wires, one extending along each side of a frame member 14. The lower spreader at the rear of the device is also preferably formed of rigid wire and is of substantially U-shape, having longitudinal portions 67 which are secured to the inner surfaces of the panels 15 or to the framework supporting said panels, said portions 67 extending longitudinally rearwardly upwardly and thence diverging laterally outwardly at portions 68 which are also rearwardly and upwardly inclined. The portions 68 are joined by a transverse portion 69. The width of the portion 69 is preferably greater than the width of the frame of the device, i. e. longer than the frame members 40, and is positioned at a level or elevation substantially the same as the level or elevation of the feeding station of an ironing machine (not shown).

Each of the panels 15 has a plurality of apertures 70 formed therein in spaced relation. As here illustrated, the apertures 70 are spaced substantially uniformly along the length of the panel in a single horizontal row or series. It will be understood, however, that a number of rows or series of these openings may be provided. Each of these openings receives a jet or nozzle 71, best shown in Fig. 3, the jet or nozzle preferably being positioned within the opening 70 but not projecting beyond the outer surface of said panel. The jets 71 are mounted upon short conduits 72, here illustrated as being slightly bent along their length, each of which conduits is connected by means of a T-fitting 73 with a conduit 74. A conduit 74 extends lengthwise of each of the panels 15, and the forward ends of said conduits preferably extend downwardly at 75 and may be connected to any suitable source of air under pressure. Each of the conduits extends adjacent to the rear end of an arm 61 of the lower front spreader and mounts a T-fitting 76, by means of which the end of said lower front spreader is connected to the compressed air line or lines.

In the use of this device a container of washed or laundered items is placed in front of the device, for example below the spreader unit 61-63, and an operator stands in front of the device within reach of the laundry carrier and of the feed end of the conveyor of the device. It will be understood that the device when conditioned for operation will entail driving of the lower belt by the operating motor 35, causing the run 18 of the belt to travel from the right to the left, as illustrated in Figs. 1 and 2. This causes similar movement from right to left of the lower run 56 of

the belt 55, 56. Also the line 75 will be connected with an air compressor or other source of air under pressure, which air is ejected in jets at the apertures 64 of the front lower spreader 61-63 and at the nozzles 71 illustrated in Fig. 3.

The operator grasps a work piece, such as a sheet, a towel, pillowcase, bedspread or table-cloth, adjacent the center of one edge or margin thereof and lifts the sheet, placing the said central portion upon the run 18 of the lower belt to cause it to enter between the belt runs 18 and 56. The work piece is permitted to hang freely from the part which is grasped during the movement, and in the movement to insert the sheet into feeding position the side and trailing end portions thereof drape around the upper spreader 57-59 and the lower spreader 61-63. As the conveyor continues to operate, the work piece is moved horizontally from the right to the left in the device, the only attention being required in the initial feeding operation being to insure that the work piece is substantially squared so that it will extend substantially parallel to the belt runs 18 and 56 as it is propelled by the conveyor. The conveyor belt runs 18 and 56 are so positioned as to grip the work piece with a friction grip sufficient to insure that the work piece will be propelled longitudinally of the device. As the leading portion of the work piece progresses, it is spread laterally by the upper and lower spreaders 57-59 and 61-63, causing the side portions of the work piece to assume an inclined position by reason of the greater width of the lower spreader 61-63 as compared to the upper spreader. Consequently, as the work piece is propelled and reaches the panels 15, it will be suspended from between the belt runs 18 and 56 with its side portions bearing in face engagement with at least a part of each of said panels 15. As the work piece is fed into the machine, the weight of its trailing portion tends to extend it longitudinally, and the free suspension of its side portions tends to extend it transversely. Thus by the time the entire work piece is gripped between the conveyor belts 18 and 56, which belt runs will preferably be of a length in the neighborhood or ten feet, or longer than the length of the work piece, the work piece will have been extended and the major folds and wrinkles thereof will have been removed incident to such extension. It will be understood, of course, that the dimension of ten feet mentioned is illustrative and is not intended to be limiting, inasmuch as the device will operate satisfactorily in cases where the belt runs 18 and 56 are much shorter and even in cases where such runs are shorter than the length of the work piece.

When the leading edge portion of the work piece approaches the discharge end of the machine, that is, when it passes beyond the rear ends of the panels 15, it engages the rear spreaders 65-66 and 67-69. The former prevent the work piece from following or catching upon the frame 14 which mounts the belt rollers 16 and 17, in which respect its function is the same as the function of the spreader 57-59. The lower rear spreader serves the purpose of raising and laterally deflecting the side portions at the leading edge of the work piece, bringing the opposite ends of the leading edge of the work piece to a position where they can be grasped conveniently by two operators positioned at opposite sides of the device at the discharge end, that is, operators who stand alongside the opposite portions 68 of the spreader 67-69. Thus these operators grasp the

leading edge of the work piece and shift it to a position at which it is fed into an ironing machine juxtaposed to said discharge station.

The ironing machines commonly used in commercial laundries are of the roller type, and the level at which the work passes through the rolls thereof is preferably substantially the same as the level at which the portion 69 of the rear spreader is positioned. The work piece will have been extended as it is discharged from the instant device so that the only requirement of the operators located at the discharge end of the machine will be to pull laterally upon the leading edge portion of the work piece and to insure that that leading edge portion is positioned substantially transversely of the direction of travel through the ironer; in other words, to be sure that the work piece will be squared with the ironing machine. Having inserted the work piece into the ironer, the same will propel or pull the work piece progressively into the ironer and only slight attention by the operators is required to keep the work piece squared and occasionally to pull longitudinally or laterally on the work piece as it is fed into the ironing machine. It will be observed that, in the event the operators stationed at the discharge end of the machine do not pay any attention to the work piece after it is properly inserted into the ironer, no danger occurs of either soiling of the work piece or catching thereof. In this connection the ironer can be set to operate at substantially the same speed of linear travel as the speed at which the belt runs 18 and 56 of the smoothing device operate, so that no tension will be exerted due to a greater speed of operation of the ironer than of the smoothing device. Furthermore, any slack in the work piece between the two devices which may occur is not critical or important inasmuch as the slack portion can rest upon and be supported by the lower rear spreader 67-69, holding the work piece out of contact with the floor or with any part of either of the devices which might be oily or soiled. The lateral divergence of the portions 68 of the rear spreader insures that the side edge portions of the work piece will be engaged at points which will prevent the work piece from touching the floor. Observe also that the rear lower spreader 67-69 projects rearwardly beyond the roller 17 so that the work piece will fall onto the spreader after its trailing edge has been released or discharged by the belt conveyor 18, 56.

The action of the air jets emitted from the apertures 64 and the nozzles 71 is of particular importance in the operation of this device. The air jets emitted from the apertures 64 assist in the extension of the work piece and the removal of folds therefrom as the work piece moves therepast. Thus the portions of the damp work piece which engage the spreader 61-63 are prevented from sticking or adhering to that spreader by reason of the fact that the air jets blow against the suspended portions of the work piece, billowing out the same at least slightly so that the work piece is out of contact with the spreader adjacent each aperture 64. In this connection the apertures 64 will preferably be formed with their axes extending substantially horizontally at the outer portion of the tube which constitutes the member 61-63. While only a limited number of apertures 64 have been shown herein, it will be understood that any number of such apertures and any location thereof found suitable may be employed, it being preferred that

said apertures will extend along each of the side runs 61, 62 in substantially uniform spaced relation.

As the work piece advances and hangs over or spans one or more of the apertures 10 of the panels 15, it is subjected to the action of the air jets emitted by the adjacent nozzle or nozzles 71. As best illustrated in Fig. 3, assuming that the work piece is traveling in the direction of the arrow, the nozzles will be so positioned that the axes thereof and of the jet of air emitted therefrom will extend at an angle and in the same direction as the work piece is moving. Consequently, if the engagement of the leading edge of the work piece with the panels 15 tends to cause that leading edge to curl or roll, the action of each of the air jets from nozzles 71 upon that leading edge portion will be to puff or billow the same outwardly with the air entering in the curled portion and acting to straighten or flatten the edge portion to remove the curl or roll therefrom. This action, coupled with the fact that the central portion of the work piece is held flat and is substantially clamped between the flat belt runs 18, 56, insures that the work piece will remain extended and that its edge will not be rolled or curled.

The beneficial effect of the air jets emitted from the nozzles 71 is not limited to the prevention of rolling or curling, however, inasmuch as they tend to billow out progressively the portions of the sheet along the full length of that sheet as the sheet progresses, by the well known Bernoulli action. In other words, the action of the air jets tends to cause vibration of the suspended side portions of the work piece, which vibration is helpful in insuring that the work piece will hang flat and that folds and creases therein will be eliminated. Consequently, by the time the work piece reaches the discharge end of the machine, it will be effectively extended, creases and folds thereof will be removed, and the requirement for a high degree of care and close attention by the operators who transfer the work piece from the smoothing machine to the ironing machine will be unnecessary.

The inclined panels 15 form means for positioning the extended side portions of the laundered article or work piece. Particularly, these panels insure that the suspended portions of the work piece will not engage each other or be adhered together, and also insures that the suspended portions of the work piece will not engage the framework of the device which supports the conveyor, the lower runs of the belt, the motor, or the motor drive. While the inclination of the panels 15 as shown is preferred, it is not essential, the important feature being that the panels or other positioning means be located below the side edges of run 18 of the conveyor belt or web. Thus the panels 15 may be positioned substantially vertically, if desired. The inclination is of advantage primarily from the standpoint of insuring that the work will normally bear in substantially flat engagement with the panel 15 and thus be located at a point to be subject to the full action of the air jets emitted from the nozzles 71. Also, it will be apparent that while the use of panels 15 is preferred, positioning means assuming other forms than panels and serving the function of holding the suspended portions of the work piece in desired relation to the nozzles 71, may be provided.

The spacing of the outer frame units comprising the parts 41-43 at each end of the device

from the frame units 11-12, the panels 15, and the conveyor run 18 and its mounting, is sufficient to insure against contact of the laundered article therewith as it is propelled through the device. Thus the spacing should be adequate to insure that the outward billowing action of the article under the influence of the air jets will not cause contact of the work piece with these outer frame parts or with the longitudinal members 44 connecting said outer frame parts. Thus the outer frame parts 41-43 bridge or arch over the central portion of the structure, thereby providing for the suspension of the mounting for the upper endless web 55, 56 and for the necessary clearance for travel of the work piece from end to end of the device out of contact with said outer frame structure. It will be understood that the use of an arching frame structure as shown is illustrative and not limiting, and that any other means, such as ceiling brackets, may be employed to suspend the frame structure 49 around which the conveyor web 55, 56 is trained.

A further advantage of the device, and particularly of the air jets therein, is that there is a tendency to remove any loose drops of water which may be carried by the sheet, thereby conditioning the work piece for quicker travel through the ironing machine than would be possible if a greater amount of moisture were present in the work piece.

Experience with this device in actual practice has disclosed that an ironing machine can be operated with a much higher output per hour, day or other unit of time than is possible where the smoothing device is not used, and the increase in output of the ironing machine more than offsets the expense of employing an additional operator whose duty it is to feed the smoothing device. This operator, being required only to grasp the central leading portion of a work piece and to insert it upon the belt conveyor, is enabled to supply a constant flow of work pieces separated only slightly as they pass through the machine one after another, thereby enabling a constant flow of smoothed work pieces to be fed to the ironing machine. This is to be contrasted with previous practices in feeding ironing machines where two operators stationed at the feeding end of the ironing machine have been required to untangle and laterally extend the work piece at its leading edge and then to extend it both longitudinally and transversely as it is fed into the ironing machine. The attention of these operators to a given work piece passing through the ironing machine must continue until all of the work piece has entered the ironing machine, whereupon the operators reach for and manipulate the succeeding work piece preparatory to inserting it into the machine. The time required for the latter operation is such that substantial intervals occur in feeding successive work pieces, whereas with the present machine a substantially continuous feeding of the work pieces with only slight intervals or spacing between successive work pieces is required.

The function of a conventional commercial ironing machine and the speed of output thereof are conditioned upon several factors, namely, the size of the machine and the amount of moisture contained in the damp laundry fed thereto. Thus, if an ironing machine has a given number of heated rollers, the linear speed of travel of a work piece therethrough may be greater than the speed of travel through a device having a smaller number of heated rollers. Likewise, if the amount of

moisture contained in a work piece, as that work piece is fed into the ironer, is reduced, the speed of travel of the work piece through the ironer may be proportionately increased. An increase in output of any given ironing machine can be secured, as compared to the output possible by feeding from a smoothing device of the character shown in Figs. 1 to 3, by constructing that machine in the manner illustrated in Fig. 4.

The embodiment illustrated in Fig. 4 is preferably the same in all particulars and includes the same elements and combination and arrangement of parts as have been illustrated in Figs. 1 to 3 and described hereinabove. There is added thereto, however, an outer casing spaced outwardly from the outer frame members 41-43, which includes vertical side walls 80 and a top panel 81. These panels are preferably of a length substantially equal to the length of the panels 15 and terminate at their front and rear ends adjacent to the front and rear outer frame units 41-43. A partial housing of the unit shown in Figs. 1 to 3 is thus provided, which housing is open at its opposite ends so that the feeding and discharge stations of the smoothing device are spaced outwardly from said housing. Within this housing and mounted upon suitable supports or brackets, such as the brackets 82 shown as being carried by the side walls 80 at opposite sides of the device, are heating means 83. The heating means 83 may constitute infrared bulbs electrically energized and having reflectors cooperating therewith to direct and focus the rays against the work as the work is carried lengthwise along the device. Any selected number of heating means found desirable may be utilized. The heating means, being focused upon the suspended side portions of the work piece, have a drying action upon the work piece so that by the time the work piece reaches the discharge end of the device, it will contain less moisture than was contained therein as it was fed to the device. The drying, of course, must not be permitted to proceed to completion so that the ironing action of the ironing machine is interfered with. However, it can proceed to a point which will reduce the time required for passage of the work piece through the ironing machine. In other words, enough moisture can be removed from the work piece as it travels through the smoothing device and is acted upon by the heating elements 83 to enable the linear speed of travel of the work piece through the ironing machine to be increased and the output of that ironing machine to be similarly increased. The use of the heating elements 83 will be understood to be optional.

While the invention has been illustrated and described in Figs. 1 to 4 as requiring the use of air blasts or jets as means for vibrating the laundered items passing along the inclined panels 15, other means may be provided for vibrating the laundered items. Thus the laundered items can be subjected to vibration by mechanical means. A construction for this purpose is illustrated in Figs. 5 and 6 wherein the inclined side panels 15 of the device have formed therein a plurality of elongated rectangular apertures 90 which preferably are formed inclined slightly relative to vertical as shown, but which may be positioned with their long dimension vertical, if desired. The slots 90 will preferably extend for a substantial portion of the vertical dimension of the panels 15 but the length thereof may be substantially shorter than as here illustrated. The panels 15, or framework mounting said panels, carry suit-

able bearings which journal shafts 91, each parallel to and substantially centrally positioned between the side edges of the openings 90 but inwardly offset therefrom, as illustrated in Fig. 6. The shaft 91 may mount a cylindrical carrier of any desired construction designated in Fig. 6 by the numeral 92 and serving as a carrier for flexible flails 93. The shafts 91 are adapted to be driven by gearing or other transmission means 96 from the elongated shaft 94 which is driven or carried by a motor 95 or any other suitable driving means.

The parts are preferably so constructed that, as the laundered item 97 is propelled between the belt runs 18, 56 as above described with its opposite side portions resting upon the inclined panels 15, said side panels will be subjected to the action of the flails 93 as shown in Fig. 6, thereby causing mechanical vibration of the work piece 97 incident to its movement longitudinally of the machine. The parts are preferably so arranged and constructed that the flails 93 in passing through the opening 90 in the panel 15 will have a whiplike action upon the work piece 97. The flails may constitute cord, fabric or any other flexible element found suitable and of the character well understood in the art.

Fig. 7 illustrates a slightly different form of construction wherein the shafts 91 driven by the motor 95 mount cylindrical members 92 from which brush bristles 98 project. In other words, Fig. 7 illustrates a rotary brush whose bristles are adapted to project through apertures 90 in the panel 15 to engage and agitate the work piece 97 passing therewith.

It is frequently desirable to provide means for controlling the rate at which work pieces are fed to this device and to correlate said rate of speed with the rate at which work pieces discharged from the device can be applied to an ironer. A simple means by which the rate of feeding of the work can be governed or controlled is illustrated in Fig. 2, wherein the numeral 100 designates a suitable guide extending lengthwise of the machine and illustrated as being supported upon the longitudinal frame members 44 at the top of the device. Upon this guide is mounted slidable bracket 101 which may carry a mirror 102. The mirror is so positioned and carried at such an angle that the operator who feeds the machine, by viewing the same in the approximate direction of the arrows 103 in Fig. 2, will observe the work positioned below the mirror. Suitable means for adjusting the position of the mirror longitudinally of the machine may be provided and, as here illustrated, the same may constitute a lever 104 pivoted to the frame of the device and connected by a link 105 to the bracket 101. As the lever 104 is swung, the bracket 101 is caused to slide on the guide 100, thereby varying the position of the mirror lengthwise of the frame. Any other suitable means for varying the position of the mirror lengthwise of the arrows may be employed.

The purpose of this construction is that for any given setting of the ironing machine to which the work pieces from the instant machine are to be fed, there will be calibrated a suitable setting of the mirror 102 so that an operator, feeding work pieces into the present machine, can do so by simply observing the time when the trailing edge of the preceding work piece passes out of his line of vision in the mirror 102. In other words, the operator picks up a piece of laundry but refrains from placing it upon the machine

until the trailing end of the work piece is no longer visible in the mirror, and then feeds the new piece into the machine. The interval of time afforded between the successive work pieces by this means insures correlation of the operating time with the time required for operation of the ironing machine.

While the preferred constructions of the device have been illustrated and described herein, it will be understood that changes may be made therein within the scope of the appended claims without departing from the spirit of the invention.

We claim:

1. A device for smoothing laundered articles, comprising a frame, an article conveyor mounted on the upper portion of said frame and including an elongated substantially horizontal run, a structure spaced outwardly from and bridging said frame, an elongated substantially horizontal web carrier suspended from said structure and including an endless web having a run in face engagement with said first named conveyor run, and means for driving said first named conveyor, said conveyor being narrow compared to said article whereby at least a portion of said article hangs downwardly from said conveyor and longitudinal guide members carried by said frame below and at opposite sides of said conveyor.

2. A device for smoothing laundered articles, comprising a frame, an article conveyor mounted on the upper portion of said frame and including an elongated substantially horizontal run, a structure spaced outwardly from and bridging said frame, an elongated substantially horizontal web carrier suspended from said structure and including an endless web having a run in face engagement with said first named conveyor, means for driving said first named conveyor, said conveyor being narrow compared to said article whereby at least a portion of said article hangs downwardly from said conveyor, and a positioning member carried by said frame and extending downwardly from at least one side of said first conveyor run to position the hanging portion of said article.

3. A device for smoothing laundered articles, comprising a frame, an article conveyor mounted on the upper portion of said frame and including an elongated substantially horizontal run, a structure spaced outwardly from and bridging said frame, an elongated substantially horizontal web carrier suspended from said structure and including an endless web having a run in face engagement with said first named conveyor run, means for driving said first named conveyor, said conveyor being narrow compared to said article whereby at least a portion of said article hangs downwardly from said conveyor, means carried by said frame and extending below said first conveyor run at the side thereof to engage and position the hanging portion of said article, and means for vibrating the hanging portion of said article.

4. A device for smoothing laundered articles, comprising a frame, an article conveyor mounted on the upper portion of said frame and including an elongated substantially horizontal run, a structure spaced outwardly from and bridging said frame, an elongated substantially horizontal web carrier suspended from said structure and including an endless web having a run in face engagement with said first named conveyor run, means for driving said first named conveyor, said conveyor being narrow compared to said article whereby at least a portion of said article hangs

downwardly from said conveyor, and means for vibrating the hanging portion of said article.

5. A device for smoothing laundered articles, comprising a frame, an article conveyor mounted on the upper portion of said frame and including an elongated substantially horizontal run, a structure spaced outwardly from and bridging said frame, an elongated substantially horizontal web carrier suspended from said structure and including an endless web having a run in face engagement with said first named conveyor run, means for driving said first named conveyor, said conveyor being narrow compared to said article whereby at least a portion of said article hangs downwardly from said conveyor, and means for discharging a jet of air under pressure transversely of the path of movement of and against the hanging portion of said article.

6. A device for smoothing laundered articles, comprising a frame, an article conveyor mounted on the upper portion of said frame and including an elongated substantially horizontal run, a structure spaced outwardly from and bridging said frame, an elongated substantially horizontal web carrier suspended from said structure and including an endless web having a run in face engagement with said first named conveyor run, means for driving said first named conveyor, said conveyor being narrow compared to said article whereby at least a portion of said article hangs downwardly from said conveyor, a positioning member located below the conveyor and engageable by the hanging portion of said article, and an article spreader projecting forwardly from said positioning means and beyond the feed end of said conveyor, the trailing end of said article being drawn over said spreading means as it is pulled into said conveyor.

7. A device for smoothing laundered articles, comprising a frame, an article conveyor mounted on the upper portion of said frame and including an elongated substantially horizontal run, a structure spaced outwardly from and bridging said frame, an elongated substantially horizontal web carrier suspended from said structure and including an endless web having a run in face engagement with said first named conveyor run, means for driving said first named conveyor, said conveyor being narrow compared to said article whereby at least a portion of said article hangs downwardly from said conveyor, and spreading means below the discharge end of said conveyor, said spreading means including a laterally outwardly extending portion engageable by the hanging portion of said article.

8. A device for smoothing laundered articles, comprising a frame, an article conveyor mounted on the upper portion of said frame and including an elongated substantially horizontal run, a structure spaced outwardly from and bridging said frame, an elongated substantially horizontal web carrier suspended from said structure and including an endless web having a run in face engagement with said first named conveyor run, means for driving said first named conveyor, said conveyor being narrow compared to said article whereby at least a portion of said article hangs downwardly from said conveyor, and an open ended enclosure housing at least an intermediate portion of said frame, conveyor, bridge structure and web carrier, and heating means in said enclosure.

9. A device for smoothing laundered articles, comprising a conveyor including a narrow endless web having a substantially horizontal upper

run, a support mounting said conveyor in an elevated position and including parts projecting laterally of said upper run adjacent the opposite ends thereof, work deflectors carried by said support below the level of said upper run and extending around said laterally projecting support parts, drive means for actuating said conveyor, article-positioning panels positioned below the opposite side edges of said web, the upper edges of said panels being positioned below the side edges of said upper web and said panels being inclined downwardly and outwardly and hold-down means including an endless web having a run normally bearing upon the upper face of the upper run of the upper run of said first named web and in frictional engagement therewith.

10. A device for smoothing laundered articles, comprising a conveyor including a narrow endless web having a substantially horizontal upper run, a support mounting said conveyor in an elevated position, drive means for actuating said conveyor, downwardly and outwardly inclined longitudinal article-positioning members having their upper end portions positioned below the opposite side edges of said web, hold-down means including an endless web having a run normally bearing upon the upper face of the upper run of said first named web and in frictional engagement therewith, and a U-shaped longitudinal article spreader extending around and beyond the feeding end of said conveyor.

11. A device for smoothing laundered articles, comprising a conveyor including a narrow endless web having a substantially horizontal upper run, a support mounting said conveyor in an elevated position, drive means for actuating said conveyor, substantially upright article-positioning members positioned below the opposite side edges of said web, and hold-down means including an endless web having a run normally bearing upon the upper face of the upper run of said first named web and in frictional engagement therewith, said article-positioning members constituting panels engageable by portions of said article suspended from the sides of said web, each panel having an aperture, and means for discharging a jet of compressed air including a nozzle located at each panel aperture.

12. A device for smoothing laundered articles, comprising a conveyor including a narrow endless web having a substantially horizontal upper run, a support mounting said conveyor in an elevated position, drive means for actuating said conveyor, substantially upright article-positioning members positioned below the opposite side edges of said web, hold-down means including an endless web having a run normally bearing upon the upper face of the upper run of said first named web and in frictional engagement therewith, said article-positioning members constituting panels engageable by portions of said article suspended from the sides of said web, each panel having an aperture, and means for discharging a jet of compressed air including a nozzle located at each panel aperture, each nozzle being positioned with its axis angularly displaced relative to the plane of the adjacent panel and to the perpendicular to direct a jet of air outwardly and forwardly in direction of travel of said article.

13. A device for smoothing laundered articles, comprising a conveyor including a narrow endless web having a substantially horizontal upper run, a support mounting said conveyor in an elevated position, drive means for actuating said

conveyor, substantially upright article-positioning members positioned below the opposite side edges of said web, hold-down means including an endless web having a run normally bearing upon the upper face of the upper run of said first named web and in frictional engagement therewith, a tubular U-shaped spreader having side runs positioned longitudinally and below the feed end of said conveyor and a central bent portion between said side runs and projecting beyond the feed end of said conveyor for engagement with said article as it is fed to and along the front portion of said conveyor, said tube having a plurality of apertures at the portion thereof engaged by said article, and means for supplying 15 gas under pressure to said tube.

14. A device for smoothing laundered articles, comprising a conveyor including a narrow endless web having a substantially horizontal upper run, a support mounting said conveyor in an elevated position, drive means for actuating said conveyor, substantially upright article-positioning members positioned below the opposite side edges of said web, hold-down means including an endless web having a run normally bearing upon the upper face of the upper run of said first named web and in frictional engagement therewith, and a spreader projecting longitudinally rearwardly below and beyond the delivery end of said conveyor and adapted for engagement with the suspended portions of said article, said spreader including rearwardly diverging article-engaging portions.

15. A device for smoothing laundered articles, comprising upper and lower endless belts, supporting means including members for training said belts in positions with substantially horizontal runs in frictional engagement, means for driving one belt, article-positioning means below the horizontal run of the lower belt and at opposite sides of the remaining portions of said lower belt for engagement by article portions depending from said horizontal belt run, and means carried by said article-positioning means for vibrating the depending portions of said article. 45

16. A device for smoothing laundered articles, comprising upper and lower endless belts, supporting means including members for training said belts in positions with substantially horizontal runs in frictional engagement, means for driving one belt, downwardly and outwardly inclined panels located below the horizontal run of the lower belt, each panel having an aperture, means for supplying gas under pressure, and a nozzle located at each panel aperture and connected with said gas supply means to discharge a jet of gas outwardly and against a depending portion of said article.

17. A device for smoothing laundered articles, comprising upper and lower endless belts, supporting means including members for training said belts in positions with substantially horizontal runs in frictional engagement, means for driving one belt, article-positioning means below the horizontal run of the lower belt and at opposite sides of the remaining portions of said lower belt for engagement by article portions depending from said horizontal belt run, and means for vibrating the depending portions of said article, a tubular spreader located below said belt runs and projecting forwardly therebeyond at the feed end thereof, and means connecting said tubular spreader to a source of gas under pressure, said spreader having an aperture for discharging a jet of gas outwardly and against an article engaging said spreader.
